UNITED STATES PATENT OFFICE.

DANIEL LASHER AND ALVIN S. PLANK, OF PORT HURON, MICHIGAN.

NOZZLE HOLDER.

Application filed March 31, 1926. Serial No. 98,892.

This invention relates to improvements in holders for use upon spray nozzles and which contemplates the provision of a supporting base providing a channel portion 5 within which the nozzle may rest and a clamp extending over an appreciable portion of the channel for securing the adjacent end of a hose therein.

Another object of the invention resides in 10 the provision of a clamp arranged upon the forward end of the hose adjacent the nozzle and having a pin pivoted thereon and extending therefrom and having its opposite end adapted for selective engagement with 15 in a plurality of spaced depressed portions provided in the channel for holding the nozzle and hose at a desired angle in spraying and watering objects at various distances and inclinations from the nozzle.

With the above and other objects in view, 20 the invention further includes the following novel features and details of construction, to be hereinafter more fully described, illustrated in the accompanying drawings and 25 pointed out in the appended claim.

In the drawing:—

Figure 1 is a side elevation of the invention as applied to a hose.

Figure 2 is a top plan view thereof.

Figure 3 front elevation of the invention, 30 as applied.

Figure 4 is a longitudinal section taken through the invention.

Figure 5 is a vertical sectional view taken 35 on line 5—5 of Figure 2.

Referring to the drawing in detail, where- 40 in like characters of reference denote corre- sponding parts, the reference character 10 indicates an elongated channel or semicir- cular plate carried by rearwardly extend- 45 ing arms 11 upon its under side and adja- cent its forward end while inwardly and upwardly extending arms 12 are disposed upon the respective ends of the arms 11 and 50 connected with the plate 10. Secured to the upper sides of the arms 12 adjacent the points of association with the plate 10 are outwardly extending apertured ears 13 pro- 55 vided upon the opposite sides of a semi-cir- cular attaching flange 14 which when asso- ciated defines a circular portion between the upper side of the plate 10 and the corre- sponding inner side within which an appreciable portion of a hose such as indicated at 55 15 may be rigidly held therebetween through the instrumentality of securing elements

such as indicated at 16. The forward por- 60 tion of the attaching flange 14 provides an upwardly extending portion 17 having an inclined portion 18 communicating with the bore thereof to permit the hose 15 to be raised to the respective dotted and full line positions as illustrated in Figure 1 of the drawings.

In order to provide means for sustaining 65 and holding the forward end of the hose 15 and the conventional form of nozzle 19 se- cured thereto at an appropriate angle we pro- vide a clamping band 19' upon the forward 70 end of the hose 15 below the nozzle 19 which pivotally supports between spaced parallel apertured ears 20 carried upon the extremi- 75 ties thereof to support a pin or bolt 21. Said bolt is passed through the upper looped end of a supporting rod 22 provided with a 80 rounded lower end adapted for selective en- gagement within any one of a plurality of de- pressed portions 23 arranged in spaced aligned relationship within the upper side 85 of the plate 10 in order that the nozzle 19 may be supported at different inclinations 90 and heights in the instance of using the nozzle as a spray.

It is further to be noted that the above 95 entitled invention may remain applied to 85 the hose and offer no resistance nor inter- ference to a person so using the hose by hand and owing to the construction thereof may be readily and easily placed upon the ground and supported at a desired inclina- 90 tion.

The invention is susceptible of various 95 changes in its form, proportions and minor details of construction, and the right is herein reserved to make such changes as 100 properly fall within the scope of the ap- pended claim.

Having thus described the invention, what 105 is claimed is:—

A hose holder comprising an elongated 100 channeled plate having a plurality of spaced aligned depressed portions arranged in the channel portion thereof, supporting arms 105 formed upon the under side and adjacent the forward end of the plate and extending outwardly and rearwardly thereof, said arms communicate with inwardly extending sup- porting arms secured to the opposite side edges of the plate adjacent the rear end portion thereof, a semi-circular attaching flange having outwardly extending aper- 110 tured ears provided upon its opposite sides

and secured to the upper side of the plate for securing an appreciable portion of the hose therebetween, the forward end of the attaching flange is upwardly inclined to permit upward swinging movement of the hose, and a clamping band secured to the forward end of the hose and having a pivotally mounted pin depending therefrom and terminating in a rounded end portion for selective engagement within any one of the plurality of depressed portions in the channelled plate for holding the forward end of the hose at a desired inclination. In testimony whereof we affix our signatures.

DANIEL LASHER.
ALVIN S. PLANK.
